CLAIM

The ornamental design for match container, as shown and described.

DESCRIPTION

FIG. 1 is a perspective view of a match container showing my new design;

FIG. 2 is a front elevational view thereof;

FIG. 3 is a rear elevational view thereof;

FIG. 4 is a side elevational view thereof, the opposite side being identical;

FIG. 5 is a top plan view thereof;

FIG. 6 is a bottom plan view thereof;

FIG. 7 is a bottom plan view of FIG. 1, the only difference being an abrasive surface;

FIG. 8 is a front perspective view of a third and fourth embodiment of the design of FIG. 1, wherein the bottom is shown in FIGS. 6 and 7, respectively;

FIG. 9 is a front elevational view of FIG. 8, the rear elevational view being identical.

FIG. 1

FIG. 2

FIG. 3

FIG. 4

FIG. 5

FIG. 6

FIG. 7

FIG. 8

FIG. 9
